US00D530043S

(12) **United States Design Patent** (10) **Patent No.:** **US D530,043 S**
(45) **Date of Patent:** **** Oct. 10, 2006**

(54) **HELMET WITH FACEGUARD**

(75) Inventors: **Frederick C. Foote**, Haslett, MI (US);
Jon D. Schiff, St. Joseph, MI (US)

(73) Assignee: **SmartGuards, LLC**, East Lansing, MI (US)

(**) Term: **14 Years**

(21) Appl. No.: **29/227,999**

(22) Filed: **Apr. 19, 2005**

(51) **LOC (8) CL .....** **29-02**

(52) **U.S. CL .....** **D29/102**

(58) **Field of Classification Search .....** D29/102-109,
D29/122; 2/10, 9, 421, 422, 423, 424, 425

(57) **CLAIM**

We claim the ornamental design for a helmet with faceguard, as shown and described.

DESCRIPTION

FIG. 1 is a perspective view of a helmet with faceguard showing my new design;

FIG. 2 is a right side view thereof, the left side being a mirror image;

FIG. 3 is a front view thereof;

FIG. 4 is a rear view thereof;

FIG. 5 is a top view thereof;

FIG. 6 is a bottom view thereof;

FIG. 7 is a perspective view of a second embodiment thereof;

FIG. 8 is a right side view of FIG. 7, the left side being a mirror image;

FIG. 9 is a front view of FIG. 7;

FIG. 10 is a rear view of FIG. 7;

FIG. 11 is a top view FIG. 7; and,

FIG. 12 is a bottom view FIG. 7.

The details shown in broken lines form no part of the claimed design.
